UNITED STATES PATENT OFFICE.

LOUIS G. COON, OF PUEBLO, COLORADO.

FASTENER FOR REFRIGERATOR-DOORS.

No. 874,833.

Specification of Letters Patent.

Patented Dec. 24, 1907.

Application filed April 18, 1907. Serial No. 363,941.

To all whom it may concern:

Be it known that I, LOUIS G. COON, a citizen of the United States, and a resident of Pueblo, in the county of Pueblo and State of Colorado, have invented certain new and useful Improvements in Fasteners for Refrigerator-Doors, of which the following is a specification.

My invention is an improvement in door fasteners and consists in certain novel constructions and combinations of parts as will be hereinafter described and claimed.

In the drawing Figure 1 is an elevation of the outside and Fig. 2 an elevation of the inner side of a door provided with my improvements. Fig. 3 is a vertical section on about line 3—3 of Fig. 2. Fig. 4 is a cross-section on about line 4—4 of Fig. 2, and Fig. 5 is a detail section on about line 5—5 of Fig. 2.

20 The door A is hinged at A' and fits in its door-frame B in the manner common to refrigerator and similar doors. The door is provided with a shaft C having a crank handle or lever D at its outer end outside the door and provided at its inner end at the inner side of the door with a lever E which may be extended at E' to form a handle so the fastening devices may be operated at the inner side of the door if so desired. On the 25 inner side of the door near its swinging edge and its opposite ends, I pivot between their ends the bolts F whose outer ends may be swung beyond the edge of the door to engage upon the inclined surfaces G' of the wedge 30 blocks G which blocks are secured to the door frame in position for engagement by the outer ends of the bolts F so that when the bolts are swung to the position shown in Fig. 2 they will be in engagement with the bevelled wedge blocks and will draw the door 35 tightly into its frame forming a close joint as desired especially in refrigerator construction.

At their inner ends the bolts F connect 40 with links H and H', the link H connecting at one end with the lower bolt F and at its other end with the lever E on the door so it may be operated thereby. The link H' connects at one end with the upper bolt F and 45 depends thence and pivots at its lower end to the link H at a point between the opposite pivots of the link H so it will be operated by the lever E through the said link H as will be understood from the full and dotted lines 50 Fig. 2. Stops I and I' limit the movements of one of the bolts in its opposite adjustments

and when the links are operated to set the bolts to locked position they stand in alignment as shown in Fig. 2. It will be noticed that the outer handle D is so arranged that 60 you lift or pull up on said lever in closing the door which operates to lift the door so it will close easily.

The wedge blocks are preferably slotted longitudinally at G² and secured by screws 65 G³ passed through said slots so the wedge blocks may be set to any desired position and firmly secured in the use of the invention. While the two fastening bolts are on the inner side of the door and independent it will 70 be noticed they are operated jointly and from the outer side of the door by a single lever. All of the fastening devices are arranged at the inner side of the door and are exposed and convenient of access for any 75 desired purpose. As best shown in Fig. 3 the upper and lower wedge blocks both slope in the same direction and are thinnest at their upper ends so the action of the bolts therein will exert a lifting tendency on the 80 door in fastening the same as before described.

I claim—

1. The combination of a door frame, wedge blocks having longitudinal slots, screws 85 passed through said slots and securing the blocks adjustably to the door frame, a door fitted to said frame, a shaft in said door and having a lever at its inner end and a handle at its outer end, bolts pivoted between their 90 ends to the inner side of the door near its opposite ends and arranged at their outer ends to engage upon the wedge blocks, a link pivoted at one end to the inner arm of one of said bolts and at its other end to the lever at 95 the inner end of the shaft, and a link pivoted at one end to the inner arm of the other bolt and at its other end to the first said link, substantially as set forth.

2. The combination with the door frame 100 having the wedge blocks and the door fitted to said frame of opposite bolts pivoted to the door and engaging upon the wedge blocks, an operating lever on the door between the bolts, a link pivoted at one end to one of the bolts and at its other end to the lever and a link pivoted at one end to the other bolt and extended at its other end past the lever and pivoted at its said end to the first link at a 105 point between the pivots thereof, substantially as set forth.

3. The combination of a door frame, a

door fitted thereto, bolts pivoted to the inner face of the door, a lever connected with and operating said bolts, wedge blocks having longitudinal slots, screws passing through 5 said slots into the door frame, and securing the wedge blocks adjustably thereto and in position for engagement by the bolts on the door, substantially as set forth.

4. The combination of a door frame, a 10 door fitted thereto, wedge blocks secured to the door frame, bolts pivoted to the door in position to engage their respective wedge blocks, operating means between said bolts, and intermediate devices between the bolts 15 and operating means substantially as set forth.

5. The combination with a door and pivoted bolts thereon of links pivoted together and also pivoted independently to their respective bolts, and means between the bolts 20

for operating the links, substantially as set forth.

6. The combination of a door frame, upper and lower wedge blocks thereon and sloping in the same direction with their thin ends 25 upward, a door fitted to said frame, bolts on the door and engaging upon the wedge blocks, and means for operating the bolts, substantially as set forth.

7. The combination of a door frame, upper 30 and lower wedge blocks thereon, a door, upper and lower bolts on the door and arranged to engage their respective wedge blocks, an operating lever between said bolts and links intermediate the said bolts and operating 35 lever, substantially as set forth.

LOUIS G. COON.
